Wesley G. Barr
ATTORNEY

UNITED STATES PATENT OFFICE.

JAMES C. WOODSON, OF MANSFIELD, OHIO, ASSIGNEE TO WESTINGHOUSE ELECTRIC
PRODUCTS COMPANY, A CORPORATION OF MICHIGAN.

OVEN.

Application filed October 29, 1920. Serial No. 420,393.

To all whom it may concern:

Be it known that I, JAMES C. WOODSON, a citizen of the United States, and a resident of Mansfield, in the county of Richland and State of Ohio, have invented a new and useful Improvement in Ovens, of which the following is a specification.

My invention relates to ovens and particularly to ventilated ovens, and it has for its object to provide relatively simple means for reducing the heat-radiation losses in such an oven.

In practising my invention, I provide a plurality of sets of walls for an oven chamber and place heat-insulating material between the walls of each set, and spacing blocks between the sets of walls. I provide ventilating openings in the inner set and in the outer set of walls, these ventilating openings being located in definite spaced relation to each other. I provide means for causing a definite circulation of air from the oven chamber through the ventilating openings in the inner set of walls, through the space between the sets of walls, and either out into the surrounding space, or back into the oven chamber, with an admixture of fresh air, if desired.

In the single sheet of drawings, Figure 1 is a view, in vertical cross-section, of an oven embodying my invention, and

Fig. 2 is a cross-sectional view of the oven on the line II II of Fig. 1.

An oven chamber 1 is surrounded by side walls 2, end walls 2^a, a bottom wall 3, and a top wall 4. These walls may be of any desired or suitable construction, but, as shown in Fig. 1, comprise plates of relatively thin sheet metal and suitable heat-insulating material located therebetween.

A plurality of ventilating openings 5 is provided in the top wall 4, and a ventilating opening 6, located in the bottom wall 3, is provided with an adjustable damper 7, to permit of varying the effective area of the opening.

A second set of walls 8, comprising spaced sheet metal plates and heat-insulating material therebetween, is located in spaced relation to the walls 2, 3 and 4. Suitable spacing members 9 are provided to maintain the two sets of walls in definite spaced relation,

providing paths for the heated fluid that flows through the ventilating openings 5 from the chamber 1.

An opening 10 is provided in one of the walls 8, this opening being substantially diametrically opposite one of the openings 5. An exhaust pipe 11 is located in the opening 10 and is provided, at its outer end, with an adjustable damper 12 to permit of varying the effective area of the passage.

An electrical heating means 13 is provided which may be of any suitable construction and which may be controlled in any suitable or desired manner.

In order to obtain a positive circulation of heated fluid into and out of the oven chamber 1, I provide a ventilating fan 14 which may be driven by a suitable motor 15. The in-take of the fan 14 is suitably connected to the exhaust pipe 11 by means of a pipe or tube 16, an adjustable damper 17 being provided to permit of varying the amount of air withdrawn from the exhaust pipe 11.

I provide a pipe 18 that is connected to the pipe 16 between the damper 17 and the fan 14 to permit of adding fresh air in any desired quantity. The exhaust side of the fan 14 is connected to the oven chamber 1 by means of a pipe or tube 19, suitable provision, comprising a plurality of spaced openings 19^a, being made to insure that the fluid pumped through the pipe 19 shall be distributed as equally as possible over the entire volume of the oven chamber.

If it is desired to rely upon the natural circulation of the heated fluid out of the oven chamber 1 and through the ventilating openings 5, it is only necessary to entirely close the damper 12 and to open the damper 7, without operating the ventilating fan 14; a constant flow of fluid will then circulate from the oven chamber 1, through the ventilating openings 5, through the space between the inner and outer set of walls and through the opening 6, back into the oven chamber. If it is desired to add a certain amount of fresh air, this may be done by opening the damper 12 to a predetermined position. If it is desired to ventilate the oven chamber without having the heated fluid return thereto, it is only necessary to close the damper 7 and to open the damper 12.

If it is desired to cause a forced circula-

tion of fluid, the motor 15 may be energized to operate the fan 14 at any desired or suitable speed. In order to cause a circulation of heated fluid without any ad-mixture, 5 it is only necessary to close the dampers 7 and 12 and to open the damper 17 in the pipe 16, with the damper 20 in the pipe 18 entirely closed. If the damper 20 be partially 10 open, a predetermined amount of fresh air will be drawn in and added to the heated fluid being circulated by the fan 14. If it is desired to cause a forced circulation of heated fluid without recirculation thereof, that is, to ensure that all the heated fluid 15 shall pass through the oven chamber only once, the dampers 7 and 17 may be closed and the dampers 12 and 20 may be opened.

The temperature of the fluid flowing 20 through the space between the two sets of walls will be only slightly lower than the temperature of the fluid in the oven chamber 1, and hence, only a small amount of heat will escape through the inner set of walls. Substantially all of the heat radiated from 25 the outer surface of the oven, that is, from the outer surface of the walls 8, will be provided by the heated fluid which is located in the spaces between the two sets of walls.

In a ventilated oven, a certain part of the 30 heated fluid from the oven chamber is, of necessity, permitted to escape to the outer atmosphere, and the use of the device embodying my invention permits of causing this heated fluid to surround the oven proper as a definite envelope of live heated fluid. Practically all of the heat radiated from the 35 outer surface of the oven walls is, therefore, furnished by this definite envelope of live heated fluid, resulting in a marked economy, 40 as regards the heat input, necessary to maintain a predetermined temperature in the chamber.

Various modifications may be made without departing from the spirit and scope of 45 my invention, and I desire that only such limitations shall be placed thereon as are imposed by the prior art or are specifically set forth in the appended claims.

I claim as my invention:

1. In a ventilated oven, the combination 50 with a set of walls enclosing a chamber and having ventilated openings, heat-insulating material located between said walls, and heating means for said chamber, of a second set of walls located outside of said first 55 mentioned walls and having a ventilating opening located on the side of said oven opposite to said first mentioned ventilating openings, heat-insulating material between said walls, spacing blocks of relatively small 60 area for spacing said sets of walls apart, the ventilating openings and the space between the sets of walls being so connected as to permit of supplying substantially all of the heat-radiation losses of the oven from the heated fluid flowing through the said 65 ventilating openings and said space.

2. In a ventilating oven, the combination 70 with a plurality of sets of spaced-apart sets of walls surrounding a chamber and provided with ventilating openings, heat-insulating material between certain of said walls, and heating means for said oven chamber, of means for causing a circulation of heated fluid through said ventilating openings and between certain of said walls, and means for permitting a predetermined quantity of said 75 heated fluid to flow into the atmosphere.

3. In a ventilated oven, the combination 80 with a plurality of sets of spaced-apart sets of walls surrounding a chamber, ventilating openings in said sets of walls, heat-insulating material between certain of said walls, and heating means for said oven chamber, of means for causing a circulation of heated fluid through said ventilating openings and between certain of said walls, means for permitting a predetermined quantity of said 85 heated fluid to flow into the atmosphere, and means for permitting a predetermined 90 quantity of fresh air to be introduced into said oven chamber.

In testimony whereof, I have hereunto 95 subscribed my name this 20th day of Oct., 1920.

JAMES C. WOODSON.
